UNITED STATES PATENT OFFICE.

GEORGE BINET DOREY, OF MONTREAL, QUEBEC, CANADA, ASSIGNOR TO NATIONAL DUMP CAR COMPANY, OF CHICAGO, ILLINOIS, A CORPORATION OF MAINE.

DOOR.

1,169,778.

Specification of Letters Patent.

Patented Feb. 1, 1916.

Application filed December 13, 1912. Serial No. 736,564.

To all whom it may concern:

Be it known that I, GEORGE BINET DOREY, residing at 29 Shuter street, Montreal, Province of Quebec, Canada, have invented 5 certain new and useful Improvements in Doors; and I do hereby declare that the following is a full, clear, and exact description of the same.

This invention relates more particularly to 10 doors for closing gravity discharge openings, such as the discharge openings of hoppers or other receptacles, being especially adapted for application to cars used for transporting grain or other comminuted material.

15 This invention has for an object to provide an improved type of door which will be proof against leakage of the grain or other material.

20 For further comprehension however, of the invention and of the objects and advantages thereof, references will be had to the following description and appended claims, and to the accompanying drawings forming part of this specification in which similar 25 reference characters indicate the same parts and wherein:

Figure 1 is a vertical sectional view of the door showing it in connection with a portion of the understructure of a car. Fig. 2 is a 30 horizontal view partly in section taken on line 2—2 Fig. 1 and looking down. Fig. 3 is a vertical section at right angles to Fig. 1 on the line 3—3 Fig. 1. Fig. 4 is an enlarged vertical section of the free side of the 35 door with the adjacent portions of the door frame.

In the drawings the door is shown as closing the discharge opening of a shallow 40 hopper located in the bottom of the car and carried by the understructure a small portion of which, comprising a center sill 1, side sill 2 and connecting cross bearers 3, is shown.

A portion of the car flooring is shown at 45 4 and side wall at 5', the flooring having the usual hinged section 4' above the hopper which is adapted to be thrown up to the position shown when the car is loaded with material to be discharged through the openings in the bottom.

The hopper is provided on three of its sides (in this instance the side nearest the center sill and the two adjacent sides) with 50 walls 5, 6 additional to the car underframe and which present at their lower edges down-

wardly projecting flanges 8, the fourth wall of the hopper being here constituted by the side sill 2 of the car to which the ends of the walls 6 are suitably attached, this side sill being of channel-shape in cross section with 60 its flanges turned inwardly toward the hopper, the bottom flange supporting and sealing the free edge of the door as will be presently pointed out, this flange being spaced slightly below the adjacent ends of the 65 downturned flanges 8.

The door is shown at 10 and is preferably provided on three sides with upwardly projecting flanges 11 adapted to inclose the flanges 8 on the hopper while the fourth 70 side of the door is left unflanged and projects over the inturned flange of the side sill by which it is supported, these flanges on the hopper and side sill constituting the door frame. This door is adapted to open 75 at the side engaging the side sill and swing down to permit of the discharge of the material and means are provided to enable the door to have lateral movement to clear such flange and swinging movement to open 80 or close. To this end I prefer to mount the door on the upper ends of a pair of rigid links 15 which are pivoted at their lower ends on brackets 16 riveted or otherwise secured to the cross bearers 3, the 85 flanges 11 having riveted thereto straps 17 to which the links pivot. As shown clearly in Fig. 1 of the drawings the links are arranged in such a manner that when the door is closed the vertical force due to gravity, in addition to forcing the free side of the door downward into tight contact with the inturned flange also prevents accidental opening of the door because the natural tendency of the latter is to move bodily 90 in the direction of its free side with respect to the link mounting, thus forcing its free edge tightly against the door frame and positively maintaining itself in closed position.

This advantageous result is obtained 100 by arranging the parts in the manner of a toggle link with the angles formed between the links and door greater than a right angle. As shown in the drawings, wooden or other suitable packing strips 19 may be interposed between the free edge of the door and the web of the side sill to insure a tight joint therebetween. Suitable means may be provided to lock the door in closed position, a tongue 20 being here shown as riveted to 110

the underside of the door adjacent the free edge thereof, such tongue projecting across the underface of the side sill and under an angular bracket 21 fixed thereto, the bracket 6 and tongue having registering perforations through which a locking pin 22 is dropped. The tongue and door form an outwardly flared opening for the reception of the wedge-like flange of the side-sill which constitutes one wall of the discharge hopper.

10 To enable the door to be released I provide on the underside thereof brackets 23 which may be struck with a suitable implement such as a hammer to force the door 15 back until the edge thereof clears the flange of the side sill while chains 24 may be attached at one end to such bracket and at the other end to the side sill to limit the downward movement of the door.

20 20. What I claim is as follows:

1. In combination, a door frame, and a hinged door projecting under the said frame on three sides and over it on the fourth side.

25 2. The combination with a receptacle presenting a door frame inclosing a gravity discharge opening, of a hinged door projecting under the door frame on three sides and over it and into the opening on the fourth side.

30 3. The combination with a receptacle presenting a door frame stationary with respect to the car and inclosing a gravity discharge opening, of a door projecting over the door frame on one side, and a swinging hinge 35 device whereby the opposite side of the door is mounted.

40 4. The combination with a door frame presenting an inturned flange on one side, of a door adapted to project over such flange on its adjacent side, and means hinging the opposite side of the door in a manner to permit both of swinging movement and bodily movement laterally.

45 5. The combination with a door frame presenting an inturned flange on one side, of a door adapted to project over such flange on its adjacent side, and means hinging the opposite side of the door in a manner to permit both of swinging movement and 50 bodily movement laterally, including a pair of pivoted links having the door pivotally connected to their free ends.

55 6. In combination, a door frame presenting downwardly projecting flanges on three sides and an inturned flange on the fourth side, and a hinged door having upwardly projecting flanges on three sides adapted to inclose the said downwardly projecting flanges, the fourth side of the door projecting 60 over the said inturned flange.

65 7. In combination, a door frame presenting downwardly projecting flanges on three sides and an inturned flange on the fourth side, and a door having upwardly projecting flanges on three sides adapted to inclose the

said downwardly projecting flanges, the fourth side of the door projecting over the said inturned flange, and means hinging the opposite side of the door in a manner to permit both of swinging movement and 70 bodily movement laterally.

8. In combination, a door frame presenting downwardly projecting flanges on three sides and an inturned flange on the fourth side, and a door having upwardly projecting flanges on three sides adapted to inclose the said downwardly projecting flanges, the fourth side of the door projecting over the said inturned flange, and means hinging the opposite side of the door in a manner to 75 permit both of swinging movement and bodily movement laterally including a pair of pivoted links having the door pivotally connected to their free ends.

9. In combination, a door frame presenting downwardly projecting flanges on three sides and an inturned flange on the fourth side, and a door having upwardly projecting flanges on three sides adapted to inclose the said downwardly projecting flanges, the fourth side of the door projecting over the said inturned flange, such door having a link 80 mounting adapted to cause the force of gravity to act to hold the door in its position projecting over the said inturned flange.

10. In a car having an understructure including a side sill presenting an inturned flange at its lower side, a hopper having one wall thereof constituted by such side sill, such hopper having a discharge opening in its bottom, and a door closing such discharge opening and having one side thereof projecting over the said inturned flange.

105 11. In a car having an understructure including a side sill presenting an inturned flange at its lower side, a hopper having one wall thereof constituted by such side sill, the remaining walls of the hopper presenting downwardly projecting flanges, such hopper having a discharge opening in its bottom inclosed by the said flanges, and a door closing such discharge opening and having upturned flanges on three sides inclosing the said downwardly projecting flanges and the remaining side thereof projecting over the said inturned flange.

115 12. In combination, a door frame, and a door projecting under the said frame on three sides and over it on the fourth side, and a packing strip interposed between the edge of the door and the frame on the last mentioned side.

120 13. In combination, a door frame presenting downwardly projecting flanges on three sides and an inturned flange on the fourth side, and a door having upwardly projecting flanges on three sides adapted to inclose the said downwardly projecting flanges, the fourth side of the door projecting over the 125 130

said inturned flange, and a packing strip interposed between the edge of the door and the frame on the last mentioned side.

14. In combination, a door frame, a hinged door projecting under the said frame on three sides and over it on the fourth side and means for locking the door in such position.

In testimony whereof, I have signed my name to this specification, in the presence of 10 two subscribing witnesses.

GEORGE BINET DOREY.
